UNITED STATES PATENT OFFICE

2,428,465

DRAW MECHANISM OF STRAIGHT BAR
KNITTING MACHINES

John E. Lynam, Mapperley, and Patrick G. McCarthy, Whitwick, England, assignors to William Cotton Limited, Loughborough, England

Application May 2, 1945, Serial No. 591,464
In Great Britain January 6, 1945

15 Claims. (Cl. 66—110)

1

In Cotton's patent and other straight bar knitting machines, it is usual to reciprocate certain members (such as carriers and slurcocks) along the length of the line of needles by draw or Coulier mechanism including an upstanding draw lever which is pivoted at its lower end and oscillates in a vertical plane extending lengthwise of the machine. This oscillating draw lever has certain disadvantages. Because of the area which it sweeps out in its oscillation it unduly restricts the space whereat controls and other members extending from front to rear of the machine may be located, and the fact that it oscillates introduces undue complexities in the design of a draw cam to give the required motions to the carriers and slurcocks. An object of the present invention is a construction of Coulier or draw mechanism which obviates or minimises these disadvantages, and another object is a construction of draw mechanism which facilitates the use of an hydraulic driving coupling, of the piston and cylinder type, as described in the Specifications of British Letters Patent Nos. 565,240 and 565,268, since it permits the coupling to be installed in the machine at a location remote from the member that it drives.

The present invention provides in Coulier or draw mechanism for a Cotton's patent or other straight bar knitting machine incorporating a driven member movable to and fro rectilinearly and a driver, below it, also movable to and fro; a connection for driving said member from the driver comprising an upstanding rotary spindle. This connection occupies but little space compared with that swept out by a draw lever, and more room is therefore available for controls and other members extending from front to rear.

Preferably the driving member is movable rectilinearly and rack-and-pinion gearing is provided coupling the upper and lower ends of the spindle to the driver and driven member respectively. This construction simplifies the design of a draw cam which reciprocates the driving member.

The invention further provides a Coulier or draw mechanism for a straight bar knitting machine incorporating a reciprocable driven member and, below it, a reciprocable driver; a hydraulic driving apparatus for the latter, and an upstanding rotary spindle, and gearing, for driving the driven member from the driver.

These and other features of the invention set out in the appended claims are incorporated in the Coulier or draw mechanism that will now be

2

described, as an example, with reference to the accompanying drawings in which—

Figure 1 is a sectional elevation, taken in a plane at right angles to the length of the machine, showing the relevant parts, and

Figure 2 is a rear elevation thereof, partly in section.

In these drawings, only those portions of a Cotton's patent or other straight bar knitting machine are shown that will assist in an understanding of the invention. Longitudinal members of the machine frame are indicated at 23 and 24; 25 is the main cam shaft which drives the draw cam shaft 25' (extending from front to rear) at 10 half speed in the usual manner, this shaft carries draw cam 27 which engages trucks 28' on the draw bar 28 and reciprocates the latter lengthwise of the machine in suitable guides 30. 31 indicates the needle bar carrying needles 32, 33 the sliders, 34 the jacks, 35 the slurcocks, 36 the slur bar, 19 a carrier rod and 29 a carrier. It will be understood that the carrier rod 19 and the slur bar 36 reciprocate along the needle line in suitable guides which it is unnecessary to illustrate, and that whereas these parts are in the upper region of the machine the cam shafts, draw cam, and draw bar are in the lower region. The draw bar 28 is provided with a rack of teeth 37 engaging a pinion 38 on the bottom end of a 20 vertical hollow spindle 39 which at its upper end has a gear 40 engaging a rack of teeth 41 on a member (such for example as the slur bar 36) which requires to reciprocate with constant amplitude with the result that as the draw bar 28 reciprocates the spindle 39 revolves to and fro 25 and the slur bar 36 or the like is reciprocated.

Parallel with the draw bar 28, there is a second bar 40 reciprocable in suitable guides 30, which bar 40 is driven hydraulically—preferably by a coupling 10 according to the aforesaid specifications, so that its traverse may be varied. Reference is to be made to the specification for details but it may here be explained that the coupling 10 consists of a cylinder 11 connected 45 to one bar (here shown as being the draw bar 28), a piston 12 working therein and connected to the other bar 40 by a piston rod 13, a by-pass conduit 20 communicating between opposite ends of the cylinder 11, control valve means 21 controlling 50 said conduit 20 so that when the latter is closed the coupling drives as a solid unit and when it is open relative movement can take place between the cylinder 11 and piston 12 and the coupling is free, and adjustable valve-operating means 21a, 21b for operating the control valve means.

The variable-stroke second bar 40 has a rack of teeth 43 engaging a pinion 44 on the bottom end of a second vertical spindle 45 that is supported in suitable bearings 46 and extends up through the interior of the hollow spindle 39 (the latter being conveniently journaled on it by needle roller bearings 47 or the like). At its top end the second spindle 45 has a gear 48 meshing with a rack of teeth 49 on the carrier rod 19, so that as the draw bar 28 reciprocates the carrier rod 19 is driven hydraulically to and fro with a traverse determined by the setting of the valve-operating means 21a, 21b. The said means is adjustable with the carrier stops 26, so that as the carrier rod 19 strikes a stop at the end of its travel the valve 21 is operated to free the coupling 10 with the result that during the subsequent travel of the slur bar 36 and draw bar 28 the cylinder 10 slides over the piston 12 and hydraulic fluid is pumped through the conduit 20 from one side of the piston to the other, until such time in the reverse travel of the draw bar and slur bar the conduit 20 is closed to cause the coupling 10 to pick up the drive. It may here be pointed out that it is difficult to install hydraulic driving apparatus adjacent to the member, such as a carrier rod 19 or the like, that it is to drive because of the complexity of mechanisms adjacent to the needle row, but the foregoing driving mechanism permits it to be installed with convenience at a remote location. In the illustrated construction the hydraulic coupling 10 is installed in the lower regions of the machine, adjacent to the draw bar 28, and it will readily be appreciated that the comparatively slender driving connection afforded by shafts 39 and 45 renders available ample space for the passage of controls and the like between front and rear of the machine (i. e. through the plane of the paper in Fig. 2).

It will be noticed that the hydraulic coupling 10, of the piston and cylinder type, has a closed circuit for the hydraulic fluid; that is to say the coupling contains a certain constant volume of fluid that is never discharged therefrom. This is advantageous.

The rack-and-pinion gearing may be multiplying gearing, that is to say the gear at the top of either or each shaft may be larger than the pinion at the bottom so that only a comparatively small draw bar motion is required.

We claim:

1. In Coulier or draw mechanism for a straight bar knitting machine incorporating a driven member movable to and fro rectilinearly and a driver, below it, also movable to and fro; a connection for driving said member from the driver comprising an upstanding rotary spindle means connecting the driver to the lower end, and means connecting the driven member to the upper end, of said spindle.

2. In Coulier or draw mechanism for a straight bar knitting machine incorporating a draw cam, a draw bar reciprocated thereby, and a driven member reciprocated adjacent to the needle line by the draw bar; a driving connection between the draw bar and said member comprising an upstanding rotary spindle, rack-and-pinion gearing at the lower end of said spindle connecting said lower end with the draw bar and rack-and-pinion gearing driving the said member from its upper end.

3. In Coulier or draw mechanism for a straight bar knitting machine incorporating a reciprocatable driven member and, below it, a recip-

rocatable driver; hydraulic driving apparatus for the latter, and an upstanding rotary spindle, and gearing, for driving the driven member from the driver.

5. In Coulier or draw mechanism for a straight bar knitting machine of the kind incorporating two driven members movable to and fro, one with a constant amplitude and the other with a variable amplitude, and a common draw member which is reciprocated with a constant amplitude and which drives both the driven members; the combination of a rotary spindle for driving the first driven member from the common draw member, and an hydraulic coupling and a second rotary spindle for driving the other driven member from the common draw member and means controlling said hydraulic coupling to vary the amplitude of traverse of said other member.

6. Apparatus according to claim 4, wherein one of the spindles is hollow and the other is located inside it.

7. In Coulier or draw mechanism for a straight bar knitting machine of the kind having two members movable to and fro along a line of knitting instruments and driving apparatus therefor located at a lower level; an upstanding hollow spindle for driving one member from the driving apparatus, a second spindle extending in the interior of the hollow spindle for driving the other member from said apparatus, means connecting the lower ends of said spindles to the drawing apparatus, and means connecting their upper ends to the respective members driven by them.

8. In Coulier or draw mechanism for a straight bar knitting machine of the kind having a member movable to and fro along the needle line with a constant amplitude; a carrier movable to and fro along said line with a variable amplitude, and driving apparatus for driving said member and carrier, said apparatus including a driver movable to and fro with a constant amplitude; the combination of two rotary spindles for driving said member and carrier respectively from the driver, and a traverse-varying coupling interposed between the driver and the carrier-driving spindle for varying the amplitude of travel of the carrier.

9. A combination according to claim 7, wherein in the coupling is an hydraulic coupling having a closed circuit for the hydraulic liquid and valve means controlling said circuit for rendering the coupling operative and inoperative.

10. In Coulier or draw mechanism for a straight bar knitting machine of the kind having a member movable to and fro along the line of needles with a constant amplitude, a carrier movable along said line with a variable amplitude, and a draw bar reciprocatable with a constant amplitude for driving the member and carrier; the combination of a rotary spindle for driving the said member from the draw bar, a second reciprocatable bar adjacent to the draw bar, a traverse-varying coupling connecting the draw bar to the second bar to drive the latter, control means for rendering said coupling operative and inoperative and for thereby varying the traverse of the second bar, and a rotary spindle for driving the carrier from the second bar.

11. A combination according to claim 9, having rack-and-pinion gearing for driving each spindle and for driving the said member and carrier from their respective spindles, and having one of the spindles hollow with the other inside it.

11. In a straight bar knitting machine of the kind having a slur cock movable to and fro along the needle line with a constant amplitude of travel, a carrier movable therealong with a variable amplitude, a draw cam in the lower regions of the machine rotatable about an axis which extends from front to rear of the machine, and a draw bar reciprocated lengthwise of the machine by the draw cam; the combination of a rack of teeth reciprocated by the draw bar with a constant amplitude, an upstanding rotary shaft, a pinion at the lower end thereof driven by said rack, a rack of teeth connected to the slur cock, a gear on the top end of the shaft driving the last-said rack, a second reciprocatable bar adjacent the draw bar, a traverse-varying coupling connecting it to the draw bar, a second upstanding rotary shaft, rack-and-pinion gearing connecting its lower end to the second bar, and rack-and-pinion gearing for connecting its upper end to the carrier—whereby the latter is driven through the medium of the coupling.

12. In the Coulier or draw mechanism of a straight bar knitting machine of the kind incorporating a member movable to and fro along the needle line; the combination of hydraulic driving apparatus located at a station remote from said member and needle line, and rotary driving connections for transmitting the drive from said apparatus to the member.

13. In the Coulier or draw mechanism of a straight bar knitting machine of the kind incorporating a member movable to and fro along the needle line with a variable amplitude of travel; the combination with a driver, movable to and fro, and a traverse-varying hydraulic cou-

5

pling driven thereby, which driver and coupling are located at a station remote from the said member, of rotary driving connections for transmitting the drive from the coupling to the said member.

10

14. In the Coulier or draw mechanism of a straight bar knitting machine of the kind incorporating a member movable to and fro along the line of needles, and a draw member movable to and fro to drive it; the combination of a hydraulic coupling of the piston-and-cylinder type driven by the draw member, and rotary driving connections for transmitting the drive from the coupling to the aforesaid member.

15

15. In the Coulier or draw mechanism of a straight bar knitting machine incorporating a member movable to and fro along a line of needles; the combination of hydraulic driving apparatus, of the piston-and-cylinder type, located at a station remote from said member for driving it, and rotary driving connections extending between said apparatus and said member.
